UNITED STATES PATENT OFFICE.

JOSEPH ISIDORE LE BEL, OF MONTREAL, QUEBEC, CANADA.

PIPE.

Application filed June 17, 1922. Serial No. 569,024.

To all whom it may concern:

Be it known that I, JOSEPH ISIDORE LE BEL, a subject of the King of Great Britain, residing at Montreal, Province of Quebec, Canada, have invented certain new and useful Improvements in Pipes; and I do hereby declare that the following is a full, clear, and exact description of the invention, such as will enable others skilled in the art to which it appertains to make and use the same.

The primary object of this invention, which is a smoking pipe, is the provision of means for retaining moisture and nicotine from the tobacco in such a manner that the same cannot be drawn into the mouth through the same. The invention resides in the formation of a moisture chamber in the stem of the pipe, the chamber being formed separate from the passage and in communication therewith only through the bowl.

A further object of the invention is a pipe so constructed that during the operation of smoking, there will be no suction on the nicotine deposited in the bowl.

As a pipe is smoked, the tobacco is converted into a number of elements including smoke and nicotine. An additional feature of the invention lies in the fact that two of these elements, namely smoke and nicotine, are separated in the bowl, and are subsequently prevented from mixing with one another after separation. In this respect, the invention is to be distinguished from other pipes, in which the smoke and nicotine are drawn together into the stem and are supposed to separate on their way to the mouth-piece.

More specifically, the invention makes use of a moisture chamber formed in the stem of the pipe and beneath the draft passage. In order to avoid the entrance of nicotine and moisture into the draft passage, the interior of the bowl is provided with a projection disposed above the draft passage. By this means, the moisture and nicotine avoid said draft passage and are directed downwardly in the direction of the moisture chamber, the entrance end thereof being of such configuration and disposition as to readily receive the moisture and nicotine which is urged downwardly as the burning of the tobacco continues. In this connection, it is to be noted that during the burning of the tobacco, the heat generated has the effect of forcing the moisture and nicotine downwardly, so that the tendency

of such moisture and nicotine to proceed towards the moisture chamber is positive rather than incidental.

The invention is illustrated in the accompanying drawings, in which:

Figure 1 is a longitudinal section through the pipe;

Figure 2 is a similar view of the mouth-piece;

Figure 3 is a similar view of the bowl and stem; and,

Figure 4 is a section on the line 4—4 of Figure 1.

Referring to the drawings by reference numerals, the pipe consists of a hollow bowl 1 provided with a stem 2. A draft passage 3 is formed through the stem and communicates with the bowl in the usual manner. A moisture chamber 4 is cut through the stem in substantial parallel relation with the draft passage, and is disposed therebeneath. This chamber also communicates with the bowl, as at 5, the opening 5 being spaced inwardly from the inner end 3' of the draft passage. The mouth-piece 6 is connected to the stem by means of an abutment 7 which is threaded for engagement with the forward portion 8 of the moisture chamber. The stem has formed therein the usual passage 9 which communicates with the passage 3 when the stem is turned into its proper position. It is to be noted that the joint between the draft passages through the mouth-piece and stem 90 is flat in contrast with the usual threaded joint found in the corresponding position in other pipes. It is well known that where a screw joint occurs in the draft passage, there is an accumulation of nicotine and other clogging substances. This inconvenience is eliminated by means of the flat joint described above.

A strip of absorbent material 10 is inserted in the abutment 7 and extends into the chamber 4. This material serves to take up the moisture as the latter deposits in the chamber, and can be renewed as often as desired by merely supporting the mouth-piece from the same. The chamber 4 may be provided with a tubular lining of glass, aluminum, or similar non-absorbent material, so that the moisture received in this chamber cannot permeate into the wooden walls.

The curvature of the cavity in the bowl is such that there is formed a projection

1' above the inner end of the draft passage 3. As the result of this construction, the nicotine and moisture which are forced downwardly as the burning continues, are 5 simultaneously directed somewhat laterally in order to avoid entering the draft passage. Consequently this material enters the moisture chamber through the opening 5, the latter extending beyond the inner end of 10 the draft passage 3, as a result of which the entrance of the moisture and nicotine into the chamber 4 is greatly facilitated. It will be observed that the moisture chamber 4 has absolutely no direct communication with the draft passage 3, whereby any 15 possibility of the moisture entering the draft passage is eliminated.

In the ordinary use of a pipe, the burning tobacco is changed to ashes, and the 20 moisture and nicotine from such burnt tobacco is forced downwardly into the bowl under the action of the heat produced. Consequently, the moisture concentration of the remaining tobacco increases as the smoking 25 progresses. Finally the concentration of the moisture becomes so great that the tobacco at the bottom of the bowl is saturated with it, and such moisture is then drawn through the stem and mouth-piece. In the present 30 invention, the elements produced in the burning, including the smoke, are separated in such manner that the smoke and moisture follow different paths. Specifically, the moisture and nicotine are prevented from 35 entering the draft passage 3 by means of the projection 3', as already pointed out. Under the burning of the tobacco, the moisture and nicotine are forced downwardly into the opening 5, thereafter being absorbed 40 in the chamber 4. The smoke, being lighter than the moisture and nicotine, is affected by the draft produced in the draft passage, whereupon it is pulled therein. Because of the space between the inner 45 end of the passage 3 and the opening 5, an excessive draft through the smoke passages will not lift the moisture from the chamber 4, especially when the same has been absorbed in the substance 10. It has 50 been found that even an excess of draft through the smoke passages will not raise the moisture of the moisture chamber. In fact, it is physically impossible to raise such moisture and nicotine after the same have 55 reached a level below the lower wall of the

draft passage 3, especially since there can be no circulation of air through the moisture chamber, the end 8 thereof being closed.

While a specific embodiment of the invention has been illustrated and described, it 60 is to be understood that various alterations in the details of construction may be made without departing from the spirit of the invention as indicated by the appended claims.

Having thus fully described the invention, what I claim as new and desire to secure by Letters Patent is:—

1. A smoking pipe comprising a bowl and a stem, said stem having formed therein 70 a draft passage and a moisture chamber, both in communication with the bowl, said chamber being separate from the passage, and a mouth-piece having an abutment adapted to be received in said chamber. 75

2. A smoking pipe comprising a bowl and a stem, said stem having formed therein a draft passage and a moisture chamber, both in communication with the bowl, said chamber being separate from the passage, a mouth-piece having an abutment adapted to be received in said chamber, and an absorbent substance carried by said abutment and extending into the chamber. 80

3. A smoking pipe comprising a bowl and a stem, said stem having formed therein a draft passage and a moisture chamber, both in communication with a bowl, said chamber being separate from the passage and having its entrance opening disposed 90 beyond the inner end of the draft passage in the stem, and an inwardly extending projection formed within the bowl and disposed above the draft passage. 85

4. A smoking pipe comprising a bowl and a stem, said stem having formed therein a draft passage and a moisture chamber, both in communication with the bowl, said chamber being separate from the passage, a mouth-piece having a threaded abutment 100 adapted to be received in said chamber, an absorbent substance carried by said abutment and extending into the chamber, the joint between the mouth-piece and stem being flat at the junction of the draft passages therein. 105

In witness whereof I have hereunto set my hand.

JOSEPH ISIDORE LE BEL.
